UNITED STATES PATENT OFFICE.

HERMAN C. MUELLER, OF MILWAUKEE, WISCONSIN.

FOUR-POLE MAGNETO-GENERATOR.

1,394,108.

Specification of Letters Patent. Patented Oct. 18, 1921.

Application filed December 24, 1917. Serial No. 208,704.

To all whom it may concern:

Be it known that I, HERMAN C. MUELLER, a citizen of the United States, residing at Milwaukee, county of Milwaukee, and State 5 of Wisconsin, have invented new and useful Improvements in Four-Pole Magneto-Generators, of which the following is a specification.

My invention relates to improvements in 10 magneto generators and more particularly to generators which are intended to be used for ignition purposes in connection with multi cylinder hydrocarbon engines.

The object of my invention is to increase 15 the efficiency of magneto generators by providing a form of construction in which the number of effective sparks produced during each revolution of the magneto shaft may be multiplied and the speed of rotation correspondingly reduced below that required 20 for the ordinary generator having a two pole rotor, and keeping within standard dimensions.

In many of the modern internal combustion engines, the number of cylinders is multiplied to a point where the ordinary two pole magneto generator is poorly adapted 25 for use as an ignition generator for all of the cylinders, extremely high speed being required. In my improved generator, the 30 number of sparks produced is dependent not only upon the speed, but upon the number of pairs of induction segments with which the rotor is provided, said pairs of segments being offset and so arranged that 35 the segments may overlap in the segments of an imaginary cylinder defined by the peripheral margins of the rotary inductor segments without interfering with the 40 development of magnetic gaps and periodic reversals of the magnetic flux through the respective pairs of inductor segments at the proper intervals. By my invention therefore, it is possible to reverse the magnetic 45 flux through one of the respective pairs of inductor segments in the same manner as if the other pairs of pole pieces were not present in the same rotor. The strength or intensity of the magnetic field for each set of 50 induction segments is equal or substantially equal to that of a two pole rotor.

In the construction shown, the rotor is provided with four paired induction segments arranged with those of one pair advanced 55 90 degrees with reference to those of the other pair, whereby four ignition sparks

can be produced with each revolution of the shaft. Therefore it will not be necessary to revolve the shaft at more than half the speed that would be required for a two pole rotor 60 producing the same number of sparks. This construction also permits the use of a continuous shaft instead of a stub or divided shaft, as commonly used.

In the drawings—

Figure 1 is a side elevation of a magneto generator embodying my invention, portions being broken away in vertical section to expose the rotor and the induction coil located between the legs of the stationary 70 magnet.

Fig. 2 is a sectional view drawn on line 2—2 of Fig. 1.

Fig. 3 is a perspective view of the rotor and pole pieces of the permanent magnet, 75 and showing also the electromagnetic stationary inductor.

Figs. 4 and 5 are similar views on a smaller scale illustrating the rotor in two successive positions of current generation. 80

Like parts are identified by the same reference characters throughout the several views.

In the illustrated embodiment of my invention, I employ two permanent U shaped 85 magnets 1 and 2, mounted between non-magnetic end pieces 3 and 4 upon a suitable base 5 which is also non-magnetic. The end members 3 and 4 and base 5 constitute the machine frame. The shaft 8 extends longitudinally between the polar extremities of said magnets and is provided with bearings near each end carried by caps 7 which close the openings in the end plates or members 3 and 4. These openings may be large 90 enough to permit the insertion or removal of the rotor by removing either one of the caps. At one end of shaft 8 suitable timing mechanism 9 is provided, which may be carried by one of the caps 7 and may be of any 95 ordinary construction. The timing mechanism therefore requires no further description.

Between the plates 3 and 4, shaft 8 is provided with a set of non-magnetic sleeves or 100 cylinders 10 and 11, upon each of which is mounted a pair of inductor segments or arcuate magnetic bridges 12 and 13, 14 and 15 respectively. These are composed of soft iron or other magnetic or magnetizable material. Their inner surfaces fit the supporting sleeves or cylinders to which these in-

ductor members 12 to 15 inclusive are secured. Their outer or peripheral surfaces are concentric with the shaft.

The legs of the permanent magnets 1 and 2 are each provided with inwardly extending polar projections 17 and 18 and their inner faces are arcuate and disposed in circles concentric with the peripheral surfaces of the inductor members of the rotor, each pair of said inductor members revolving in close proximity to one pair of the field pole pieces 17 and 18.

19 is a coil having its core 20 substantially parallel to the shaft 8, and provided with legs or downward extensions 21 and 22. The core and its extensions are of magnetic or magnetizable material and are preferably laminated. At the lower ends of the polar extremities 21 and 22, the legs are enlarged and form segmental field pole pieces 23 and 24 respectively, the lower faces of which are curved in correspondence with the curvature of the inner faces of the pole pieces 17 and 18, the inductor members of the rotor revolving in close proximity thereto.

A condenser 25 may be conveniently located in the base 5. The field coil may be mechanically supported by the plates 3 and 4. In the construction illustrated, the field coil includes the primary and secondary windings, the magneto illustrated being of the high tension type. The primary winding has one pole grounded at 26 and its other pole connected at 27 with the interrupter of the timing mechanism. The branch line 28 leads to the condenser 25 in accordance with ordinary practice.

In Fig. 3, the armature is illustrated in neutral position, no current being generated, since the lines of magnetic flux are permitted to pass between the poles 17 and 18 through the inductor segments or bridge pieces 12 and 13 at one end of the rotor and through bridge pieces 15, the pole segment 24 of the electromagnetic field member, and thence through segment or bridge 14. But the continued rotation of the shaft, in the direction indicated by the arrow in Fig. 3, carries the bridge pieces to the positions in which they are indicated in Fig. 4, whereupon the lines of force will pass between poles 17 and 18 through bridge piece 18, core 20, and bridge piece 14. The lines of force thus introduced, through core 20, set up a current in the coil, but the rotation of shaft 8 continuing, the parts of the rotor again reach a neutral point after a one-eighth turn of the shaft. A further rotation of a one-eighth revolution brings the rotor to the position in which it is illustrated in Fig. 5 in which the magnetic flux path between pole pieces 17 and 18 will be established through bridge piece 14, the core 20 and bridge piece 12, but it will be noted that the magnetic lines of force traversing

the core 20 will be reversed in direction from that taken by the magnetic lines of force when the rotor is in the position in which it is illustrated in Fig. 4. It will therefore be apparent that, with the construction illustrated, each quarter revolution of the rotor causes a reversal in the direction of the lines of force through the core 20 and very effectively induces current in the primary circuit of the coil, this circuit being broken by the interrupter in the usual manner. A powerful current will be set up in the secondary winding of the coil which may be utilized to produce the ignition spark.

One inductor segment or bridge piece of each pair is advanced one quarter of a turn beyond the other, segment 15 in the construction shown being disposed one quarter of a turn in advance of segment 13, and segment 14 being disposed one quarter of a turn in advance of segment 12. The arcuate dimensions of the respective segments, and their disposition with reference to each other is such that whenever the magnetic circuit is broken by one of the segments of any given pair, it is simultaneously broken by the other segment of that pair, and is also simultaneously re-established in the opposite direction by the segments of the co-operating pair. Therefore, whenever the lines of force threading through the armature or inductor coil in one direction are broken by any given pair of segments, a reversal of the lines of force and of the current generated in the coil instantly follows, by reason of the action of the next pair of inductor segments which come into bridging positions between the armature poles and the magnet poles at the same instant that the magnetic circuit is broken by the inductor members of the previously acting set. By disposing the inductor members of given sets directly opposite each other, and by disposing these of each set at opposite ends of the rotor, and advancing one a quarter of a turn beyond the other in the circle of rotation, I provide a structure in which the poles of the permanent magnet are never bridged by any inductor at the time the magnetic circuit is broken by any given set of inductors. In my construction, bridging between the pole pieces 17 and 18 of the permanent magnet never occurs, except during a brief interval of neutrality midway between successive breaks in the magnetic circuit, and simultaneous reversals in the direction taken by the lines of force. In fact, any bridging that may occur between the pole pieces 17 and 18 is entirely dependent upon the vertical dimension or thickness of these pole pieces, and would not occur at all in the construction shown if their lower portions were cut away. By mounting the shaft 8 midway between the pole

pieces 17 and 18 with its axis parallel to the axis about which the curved faces of these pole pieces extend, and by providing a coil having a core adapted to establish a flux travel path alternately and in opposite directions from one of the inductor members of a pair to one of the inductor members of the other pair, I am enabled to employ a plurality of pairs of rotary inductor members revolving between permanent field magnets and to locate the segments of one pair in an advanced position with reference to each other in the circle of revolution, I thereby produce a reversal of the magnetic flux through the core of the coil as many times during a single revolution as there are pairs of inductor segments which can be brought into position for coöperation with the core piece of the coil to establish a path for the magnetic lines of force from one pole of the permanent magnet to the other, at a time when the shorter paths are interrupted by a magnetic gap.

While I have shown and described the segmental or arcuate inductor members as arranged in pairs, and while I prefer to so arrange them, in order that the inductor, as illustrated, may reverse the magnetic flux four times during each revolution of the shaft, yet I do not limit the scope of my invention to a structure in which these segments are paired. I also do not limit my-

self to any specific number of segments. While I have referred to the armature, illustrated in the drawings, as a rotor, it will, of course, be understood that it is not essential that the rotor should perform complete revolutions, since the same results could be secured by oscillating the rotor, and I wish to be understood as using the term "rotor" in the generic sense.

I claim:

A magneto generator comprising a magnet having opposed pole pieces, a generating coil, a core and pole pieces for said coil, a rotor mounted between said first mentioned pole pieces and having its axis extending longitudinally thereof, said rotor comprising a pair of spaced arcuate inductors at each end and adapted to magnetically link said first and second mentioned pole pieces to alternate the direction of magnetic flux through said generating coil, said arcuate inductor members arranged to completely bridge said first mentioned pole pieces immediately following each change of flux through said generating coil.

In testimony whereof I affix my signature in the presence of two witnesses.
